THERMODYNAMIC PROCESS

Application filed March 30, 1927, Serial No. 179,675, and in Sweden March 31, 1926. Renewed February 16, 1931.

The object of the present invention is to provide an improved process of refrigeration. The improved process will be readily understood by reference to the following description taken in connection with the accompanying drawings, on which:

Fig. 1 is a graphic representation of the cycle process of a refrigerant in an ordinary type of absorption refrigerating apparatus;

10 Fig. 2 is a graphic representation of the cycle process of a refrigerant in accordance with the present invention;

15 Fig. 3 is a graphic representation of a modified cycle process in accordance with the invention;

Fig. 4 is a diagram of curves for conditions of different fluids showing the relation of such curves and conditions to the invention;

20 Fig. 5 is a diagrammatic illustration of apparatus for carrying out the invention;

Fig. 6 shows, more or less diagrammatically, an apparatus for carrying out the invention embodying no moving parts;

25 Fig. 7 shows diagrammatically an apparatus for carrying out the invention comprising circulations for four fluids;

Fig. 8 shows a modification of the apparatus of Fig. 7;

30 Fig. 9 shows graphically the cycle progress of one fluid in the process of the apparatus of Figs. 7 and 8;

Fig. 10 shows graphically the cycle progress of a second fluid of Fig. 7;

35 Fig. 11 shows a graph of the process of a fluid in a system under different conditions; and

Fig. 12 is a different process graph under different conditions.

40 Referring more particularly to Fig. 1, the abscissas represent values of absolute temperature and ordinates represent the logarithm of values of pressure. In the diagram: *a* represents the condition in the evaporator; *b* represents the condition in the absorber; *c* represents the condition in the boiler; and *d* represents the condition in the condenser. The lines *a*—*d* and *b*—*c* are drawn straight and parallel which is not strictly in accordance with actual conditions but is sufficiently close for present purposes.

The process of the present invention is diagrammatically illustrated in Fig. 2. It will be noted that points *c* and *d* have the same values. In other words, lines *a*—*d* and *b*—*c* meet at point *cd*.

It is characteristic of such a process *a*—*b*—*cd*—*a* not only that the boiler and the condenser have the same temperature and pressure, but also, that all the heat which is liberated in the condenser is conducted to the boiler. In every absorption refrigerating process, where the heat liberated in the condenser is conducted to the boiler either by means of another process or, as in the process *a*—*b*—*cd*—*a*, spontaneously, considering the process as a whole, the highest conceivable efficiency $\eta_{\max}$ is:

$$\eta_{\max} = \frac{T_a \cdot T_c - T_b}{T_c \cdot T_b - T_a};$$

when T_a represents the absolute temperature of the evaporator, T_b represents the absolute temperature of the absorber; and T_c represents the absolute temperature of the boiler.

From this equation it will be seen that the temperature of the condenser is not included in the equation, of which temperature the efficiency thus is independent. This is manifestly the most important feature of this kind of process, where heat is conducted spontaneously from the condenser to the boiler, that is a process as *a*—*b*—*cd*—*a*, where the condenser and the boiler have the same temperature, or as shown in Fig. 3, a process *a*—*b*—*c*—*d*—*a*, where the temperature of the condenser is a little higher than that of the boiler, which in the practice always will be the case.

If in a process *a*—*b*—*cd*—*a*, in accordance with Fig. 2, the temperatures of the evaporator and the absorber are given, the efficiency is determined only by the temperature of the boiler. This again is a function only of the inclination of the lines of state *a*—*d* and *b*—*c*. In general a little alteration in the inclination of the lines corresponds to a relatively great alteration in the boiler-temperature. Because it is possible to vary the inclination of the lines freely and arbitrarily

within certain bounds, the efficiency of an absorption refrigerating apparatus working in accordance with the diagram $a-b-cd-a$, in Fig. 2, may be freely varied within certain bounds.

In Fig. 4 the (log. $p-T$)-curves for ammonia (NH_3) dissolved in different liquids are shown. From the figure it will be seen that the curve is steeper for ammonia dissolved in calcium chloride and water ($\text{CaCl}_2 + \text{H}_2\text{O}$) than for ammonia dissolved in pure water (H_2O).

By varying the percentage of calcium chloride it is possible to vary the inclination of the (log. $p-T$)-curve within the bounds which are decided by the two curves mentioned. In the figure some other curves are shown for ammonia dissolved in other media such as phenol ($\text{C}_6\text{H}_5\text{OH}$), glycol

20 $[\text{C}_2\text{H}_4(\text{OH})_2]$

and others.

It is clear that if the media, which corresponds to the line $a-d$, do not mix at the boiler-temperature with those corresponding to the line $b-c$, these media may be allowed to come into direct contact with each other at the point cd . If, on the other hand, they mix with each other, they can not be allowed to come into direct contact, but only gaseous ammonia should be conveyed from c to d . It is also possible to arrange that not more water-vapor or vapor of other media will be conveyed from c to d than from a to b .

35 In Fig. 4 the (log. $p-T$)-curves are shown for ammonia dissolved in the following media, which may be used in processes according to the present invention:

40 (1) Water-solution of strontium chloride (SrCl_2), saturated at 15°C . and 37°C .

(2) Water-solution of ammonia nitrate (H_4NNO_3), saturated at 15°C .

(3) Water-solution of calcium chloride (CaCl_2), saturated at 15°C . and 37°C .

45 (4) Mixture of crystallized calcium chloride (CaCl_2), ammonia chloride (H_4NCl), ammonia iodide (H_4NI) and glycerine [$\text{C}_2\text{H}_4(\text{OH})_2$] with or without addition of water, saturated at 15°C , in the diagram marked "X".

(5) Water, saturated at 15°C . and 37°C .

(6) Glycol [$\text{C}_2\text{H}_4(\text{OH})_2$], saturated at 15°C .

55 (7) Phenol ($\text{C}_6\text{H}_5\text{OH}$), saturated at 15°C .

In the diagram the chemical symbols of the substances are given with indications to the respective curves. It will be clear from the diagram that, for the phase $a-cd$, the combination $\text{NH}_3-\text{H}_4\text{NNO}_3$ is suitable and, for the phase $b-cd$, for instance $\text{NH}_3-\text{CaCl}_2$.

60 As further suitable substances may be mentioned:

(8) Water-solutions of inorganic or organic salts, preferably chlorides and nitrates of lithium, calcium, strontium, zinc, copper, etc.

(9) Waterfree salts, for instance ammonia 70 nitrate,

(10) Organic or inorganic chemically combined liquids such as water, glycol, glycerine, phenol, amines, CH-combinations, etc.

(11) Mixtures of these matters with each other or with other matters, etc.

In the following, some apparatus working in accordance with diagrams $a-b-cd-a$ will be described.

In Fig. 5 is shown a diagrammatic view of such an apparatus. Letter A designates the evaporator corresponding to the point a in the diagram $a-b-cd-a$, and B the absorber, corresponding to the point b in the same diagram. The vessel CD, which may be called the boiler, is divided into two parts, C and D by means of a wall V. The boiler corresponds to the point cd in the diagram.

In this case an absorber corresponds to what was previously designated by the word condenser. A lively circulation of ammonia and ammonia-nitrate is going on between A and D through the pipes R_1 and R_2 and of ammonia and calcium chloride through the pipes R_3 and R_4 .

Through the pipes R_5 and R_6 , gaseous ammonia and inert gas are circulating, which latter, in known manner, equalizes the differences in the partial pressures of the ammonia in A and B. These circulations, for the maintenance of which manifestly only very little work is required, are, in the schematical Fig. 5, considered to be kept going by means of the pumps P_1 , P_2 , P_3 , P_4 and P_5 .

R_1 and R_2 like R_3 and R_4 are arranged in thermal contact with each other, so that heat is exchanged between the counterflowing liquid-streams. In the same manner the gas conduits R_5 and R_6 can be arranged in thermal contact with each other. For the rest, the working process of the apparatus can be directly read off the diagram $a-b-cd-a$. Thus gaseous ammonia is conducted from the right gas chamber C of the boiler to the left one D and heat through the wall V from D to C. At the same time heat is to be supplied to the boiler from outside. By means of the gas circulation between the vessels A and B gaseous ammonia is conducted from A to B, corresponding to the gas transmission from a to b in the diagram $a-b-cd-a$.

100 In the diagram of Fig. 4, the ammonia-ammonia nitrate curve, which is the $a-d$ curve of this apparatus, crosses the ammonia-calcium chloride -37°C curve, as can be readily seen. The crossing point of these curves is the condition of vessel CD of the apparatus of Fig. 5.

105 In the diagram of Fig. 4, the ammonia-ammonia nitrate curve, which is the $a-d$ curve of this apparatus, crosses the ammonia-calcium chloride -37°C curve, as can be readily seen. The crossing point of these curves is the condition of vessel CD of the apparatus of Fig. 5.

110 In the diagram of Fig. 4, the ammonia-ammonia nitrate curve, which is the $a-d$ curve of this apparatus, crosses the ammonia-calcium chloride -37°C curve, as can be readily seen. The crossing point of these curves is the condition of vessel CD of the apparatus of Fig. 5.

115 In the diagram of Fig. 4, the ammonia-ammonia nitrate curve, which is the $a-d$ curve of this apparatus, crosses the ammonia-calcium chloride -37°C curve, as can be readily seen. The crossing point of these curves is the condition of vessel CD of the apparatus of Fig. 5.

120 In the diagram of Fig. 4, the ammonia-ammonia nitrate curve, which is the $a-d$ curve of this apparatus, crosses the ammonia-calcium chloride -37°C curve, as can be readily seen. The crossing point of these curves is the condition of vessel CD of the apparatus of Fig. 5.

125 In the diagram of Fig. 4, the ammonia-ammonia nitrate curve, which is the $a-d$ curve of this apparatus, crosses the ammonia-calcium chloride -37°C curve, as can be readily seen. The crossing point of these curves is the condition of vessel CD of the apparatus of Fig. 5.

130 In the diagram of Fig. 4, the ammonia-ammonia nitrate curve, which is the $a-d$ curve of this apparatus, crosses the ammonia-calcium chloride -37°C curve, as can be readily seen. The crossing point of these curves is the condition of vessel CD of the apparatus of Fig. 5.

paratus practicable, it is of primary importance to make the liquid and gas circulations automatic, without assistance of the pumps P_1 , P_2 , P_3 , P_4 and P_5 or other movable parts.

In Fig. 6 such apparatus is shown. The reference characters A, B, CD, C, D, R_1 , R_2 , R_3 , R_4 , R_5 and R_6 correspond to the reference characters in Fig. 5. The liquid circulation 10 between A and CD is maintained in the following manner:

Gas leaves the gas chamber C through the pipe R, which ends in the upwardly extending part of pipe R_2 , which therefore may be 15 called RR_2 . Thus in the pipe RR_2 a mixture of gas and liquid is obtained, which mixture will move upwardly. The liquid thus flows out over the discs E in the vessel D, where that gas which is not already absorbed in 20 RR_2 , will be absorbed.

The liquid circulation between B and CD is obtained in the following manner:

The upwardly extending part of pipe R_3 is arranged as a coil P around the vessel D. 25 In P the liquid will boil by means of heat supplied from D and from the electric heating device F. Through P the liquid thus seethes up into vessel C.

The gas circulation through R_5 and R_6 30 is obtained by choosing an inert gas which has higher molecular weight than ammonia, for instance nitrogen.

By means of the heating device F the necessary heat is supplied as well to C and D, that 35 is CD, as to P. The heat may, of course, be supplied in other manners, for instance by means of a gas burner or the like.

Thus it will readily be seen that the process and parts of Fig. 6 are the same as of Fig. 5, 40 the difference being that the circulations are made by means of internal factors instead of being maintained by pumps.

In Fig. 7 another particular form of construction of an absorption refrigerating apparatus is shown, in accordance to the above 45 discussed theories.

x represents a substance which dissolves water unlimitedly, but only a little ammonia or no ammonia at all. The letter y designates 50 another substance, which dissolves water and ammonia but not the substance x . The substance x may be a base, suitably caustic potash or sodium hydrate dissolved in water, and the substance y may for instance be aniline. 55 The apparatus consists, as in the foregoing case, of three vessels A, B and CD. In the vessel A heat is taken up at low temperature, in B this heat is delivered to the surroundings and heat is supplied to CD at 60 high temperature.

In the vessel CD the water, under the influence of heat is transferred from the base to the aniline. Aniline and water flow through pipe R_1' to the vessel B, where the 65 ammonia coming from A through pipe R

is absorbed. Aniline, water and ammonia flow through pipe R_1'' to vessel A. Here the water is taken up by the base coming from CD through pipe R_2 , wherefore the ammonia departs in gaseous condition at low temperature and the aniline again is transferred to CD through pipe R_4 . The base with the water taken up in A is again transferred to CD through pipe R_3 . R_1' , R_1'' , R_2 , R_3 and R_4 are arranged in thermal contact with each other, so that heat is exchanged between the counterflowing liquid-streams. The liquid circulation is, according to this schematic diagram, maintained by the pumps P_1' , P_1'' , 70 P_2 , P_3 and P_4 .

In Fig. 8 another apparatus is diagrammatically shown which differs very little from the foregoing. In this case water is separated in B from the aniline-water-solution, which comes through R_1' . The water in B absorbs ammonia coming from A through R, whereafter the same flows on to A, where it is directly mixed with the base coming from CD through R_2 . The ammonia is expelled in A in gaseous condition, whereafter the water and the base return to CD through R_3 . Here the water is taken up by the aniline coming from B through R_4 , in order to again be expelled in B. The circulation in this schematic figure 85 is indicated as being maintained by means of the pumps P_1' , P_1'' , P_2 , P_3 and P_4 .

In the (log. p —T)-diagram in Figs. 9—12 are shown the cyclic processes in the two last-mentioned apparatus, first, of the ammonia 90 and second, of the water. It is assumed that all ammonia is evaporated at T_a and condensed at T_{cd} , which may be possible practically as well as theoretically.

In Fig. 9 the diagram of the cyclic process of the ammonia is shown. From this diagram it will be seen that the pressure decreases continuously from T_b to T_a , at which last temperature it suddenly increases to 110 the primary pressure $p_a = p_b$ = the total pressure in the apparatus. This discontinuous alteration of the pressure at the temperature T_a happens, when the $\text{NH}_3 + \text{H}_2\text{O} + \text{aniline}$ -solution or the $\text{NH}_3 + \text{H}_2\text{O}$ -solution respectively coming from the vessel B is mixed with the solution in A. It will be understood that this discontinuity imparts an irreversible reaction and a loss, which would be avoided, if, at the communication from b to a (Fig. 9), that is from B to A (Figs. 6, 7 and 8), water would be allowed to continuously flow over from the $\text{NH}_3 + \text{H}_2\text{O} + \text{aniline}$ -solution or the $\text{NH}_3 + \text{H}_2\text{O}$ -solution respectively to the lye, but only so much water that 115 the pressure of the ammonia would be constant from b to a , that is from B to A. As before, the ammonia would evaporate at a and condense at b and its alteration of condition would, in the diagram, be a straight 120

125 condition, in the diagram, be a straight 130

line between a and b . (In Fig. 9 this line is dotted.)

More interesting and more important is the alteration of the state of condition of the water. The apparatus corresponding to Fig. 7 will first be discussed. In its passage from B to A the water is dissolved in aniline and ammonia. In its passage from A to CD caustic potash and sodium hydrate are dissolved in the water. One will find a difference between the steam-pressure-curve for the water dissolved in aniline and the ordinary steam-pressure-curve for water, in which a salt is dissolved. It will be shown that this difference of the steam-pressure-curves is of the same importance for this process as for the aforementioned processes $a-b-cd-a$ for instance in Fig. 3.

In Fig. 10 the diagram for the cyclic process of the water is shown, I—II—III—IV—V—VI—VII—I. The same numerals occur also in Fig. 7. The pressures and temperatures at the different points may be indicated as p_1-p_{11} etc. and T_1-T_{11} etc. In the vessel CD water is driven from the lye to the aniline by means of the power p_1-p_{11} . The decrease of the pressure $p_{11}-p_{111}$ is partly of irreversible nature and causes a loss, which is explained in that water and aniline of the state III flow in into the vessel B (Fig. 7) and is there mixed with the liquid rich in ammonia. The rest of the decrease of pressure is a consequence of absorption of ammonia in the vessel B. The decrease of pressure p_V-p_{VII} is of irreversible nature and causes a loss, which is explained in that water+aniline+ammonia of the state V flows in into the vessel A and is there mixed with the liquid richer in ammonia. By means of the power $p_{VII}-p_{VII}$ the water is driven from the aniline and ammonia to the lye. From this diagram the importance of the difference between the inclination of the steam-pressure-curves will be seen, because if the curves were parallel, a diagram corresponding to Fig. 11 would be obtained instead. The pressure difference between the points VI and VII is negative in this case, which means that energy must be released in order to transfer the water to the lye in the vessel A. Further it will be seen from the diagram of Fig. 10 that the point of intersection between the lines I—VII and II—III corresponds to the point cd in the aforementioned process $a-b-cd-a$ according to Fig. 3. As the ammonia near cd , in the figure mentioned, is transferred at one and the same temperature and about the same pressure from the liquid phase $b-cd$ to $a-cd$, the water between I and II is transferred at one and the same temperature and about the same pressure from the liquid phase I—VII to II—III.

If water is expelled from the aniline in the vessel B, so that only small amounts of aniline are considered to follow the water and

ammonia from IV to V (that is from vessel B to A in Fig. 8), the diagram in Fig. 10 instead gets the appearance shown in Fig. 12. The line IV—V is here steeper than in the diagram according to Fig. 10, because the 70 aniline is not present.

It is clear that the last described principle, as the foregoing, also can be carried out for generating work. If, for instance, it is arranged so that in the vessel A (Figs. 5, 6, 7 or 8) the pressure of the ammonia is higher than in B, work is obtained, when the ammonia is transferred from A to B. The higher pressure in A may be obtained by increasing the concentration of the ammonia in A and by 80 increasing the temperature in A. If the temperature in A is thus increased to the temperature T_b of the surroundings, which is the most natural, when the apparatus is used only as a work-generating machine, the pressure 85 in A is increased, whereby, as already mentioned, work is obtained when the gas is transferred to the lower pressure in B. A machine according to Fig. 5 can for instance 90 work as a power generator, if in the conduit R_6 a power machine is inserted, in which case a pressure equalizing gas is not used and the conduit R_5 and the pump P_6 are unnecessary. With a machine in accordance with the showing of Fig. 7 a power machine for the same 95 purpose can be inserted in the conduit R between the vessels A and B. Power generation can also be effected by means of partly converting the heat energy transferred to the vessel B into work by known expedients. 100 Work-generating machines of this kind are well-known and it is not necessary to explain their construction more closely in this connection.

The above mentioned thermodynamic 105 processes can, of course, also be used in combination with heat aggregates, whereby the heat conducted to the vessel B is directly used for heating purposes.

What I claim is:

1. The process of refrigerating which comprises circulating refrigerant in a solution having a given pressure-temperature curve for conditions of operation, transferring the refrigerant to a second solution having a given pressure-temperature curve for conditions of operation which crosses the first-mentioned curve and effecting the transfer substantially at the conditions represented by the point of crossing of the curves, circulating the refrigerant in the second solution into heat exchange relation with the objective of refrigeration, expelling the refrigerant from the second solution in heat exchange relation with the objective of refrigeration to take up heat and transferring the refrigerant to the first-mentioned solution.

2. The process of refrigerating which comprises circulating a fluid in a solution 130

having a given pressure-temperature curve for conditions of operation, transferring the fluid to a second solution having a given pressure-temperature curve for conditions of operation which crosses the first-mentioned curve and effecting the transfer substantially at the conditions represented by the point of crossing of the curves, circulating fluid in the second solution into heat exchange relation with the objective of refrigeration, causing a change of state of said fluid in heat exchange relation with the objective of refrigeration in order to take up heat and transferring said fluid back to the first-mentioned solution.

3. Refrigerating apparatus comprising an absorber containing refrigerant in a solution having a given pressure-temperature curve for conditions of operation, a generator-absorber, means to circulate said solution between the first-mentioned absorber and the generator-absorber, an evaporator containing refrigerant in a solution having a given pressure-temperature curve for conditions of operation which crosses the first-mentioned curve, means to circulate the second solution between the evaporator and the generator-absorber and means to convey refrigerant from the evaporator to the first-mentioned absorber.

4. Refrigerating apparatus comprising a generator and an absorber arranged in heat exchange relation to operate at substantially the same temperature and pressure, a second absorber, means to circulate refrigerant in solution between the second absorber and generator, an evaporator, means to circulate refrigerant in solution between the evaporator and the first-mentioned absorber and means to convey refrigerant from the evaporator to the second absorber.

5. Refrigerating apparatus comprising a combined generator-absorber, a second evaporator, an absorber and means to circulate refrigerant from the combined generator-absorber to the evaporator, from the evaporator to the second absorber and from the second absorber to the combined generator-absorber.

6. Refrigerating apparatus comprising a combined generator-absorber, a second absorber, an evaporator, means to circulate refrigerant in solution between the second absorber and the generator-absorber, means to circulate refrigerant in solution between the evaporator and the generator-absorber and means to convey refrigerant from the evaporator to the second absorber.

7. The process of transforming energy which comprises the steps of circulating a fluid in a solution having a given pressure-temperature curve for conditions of operation, transferring the fluid to a second solution having a given pressure-temperature curve for conditions of operation which crosses the first-mentioned curve and effect-

ing the transfer substantially at the conditions represented by the point of crossing of the curves, expelling the fluid from the second solution and moving said fluid back into the first-mentioned solution.

8. The process of refrigerating which comprises circulating a refrigerant gas in a cycle in solution in a solvent past an inert gas, said solvent being capable of holding a relatively large proportion of the refrigerant gas at a low temperature and corresponding partial pressure of the refrigerant gas, circulating some of the same refrigerant gas in a second cycle in solution in a second solvent being capable of holding a relatively smaller proportion of the refrigerant gas at a low temperature and corresponding partial pressure of the refrigerant gas and capable of holding a relatively larger proportion of the refrigerant gas at a high temperature and corresponding gas pressure, passing the gas from the first-mentioned solvent to the second solvent at high temperature, and passing the gas from the second solvent to the first-mentioned solvent at low temperature by means of an inert gas.

9. The process of refrigerating which comprises circulating a gas in a cycle in solution in a solvent capable of holding a relatively large proportion of the gas at a low temperature and corresponding gas pressure, circulating some of the same gas in a second cycle in solution in a second solvent capable of holding a relatively smaller proportion of the gas at a low temperature and corresponding gas pressure and capable of holding a relatively larger proportion of the gas at a high temperature and corresponding gas pressure, passing the gas from the first-mentioned solvent to the second solvent at high temperature and passing the gas from the second solvent to the first-mentioned solvent at low temperature.

10. The process of refrigerating which comprises circulating an absorbent in a solution having a given pressure-temperature curve for conditions of operation, transferring the absorbent to a second solution having a given pressure-temperature curve for conditions of operation which crosses the first-mentioned curve and effecting the transfer substantially at the conditions represented by the point of crossing of the curves, absorbing a refrigerant in said second solution, circulating the refrigerant in said second solution into heat exchange relation with the objective of refrigeration and transferring the absorbent to the first-mentioned solution whereby said refrigerant is expelled from said second solution.

11. The process of refrigeration which comprises circulating an absorbent in a solution having a given pressure-temperature curve for conditions of operation, transferring the absorbent to a second solution having a given

pressure-temperature curve for conditions of operation which crosses the first mentioned curve and effecting the transfer substantially at the conditions represented by the point of 5 crossing of the curves, separating the absorbent from said second solution, absorbing a refrigerant in the absorbent, circulating the refrigerant in the absorbent into heat exchange relation with the objective of refrigeration, and transferring the absorbent to the 10 first-mentioned solution whereby said refrigerant is expelled from said second solution.

12. Refrigerating apparatus comprising a heated vessel, an absorber, an evaporator, 15 means for supplying an absorbent in solution with a first liquid to said heated vessel, means for supplying a second liquid to said heated vessel, said absorbent and said second liquid having a greater affinity for each other at the 20 temperature obtaining in said heated vessel than the affinity between said absorbent and said first liquid, whereby said absorbent passes from solution with said first liquid to solution with said second liquid, means for 25 conveying a solution comprising said absorbent and said second liquid to said absorber, means for supplying vaporous refrigerant to said absorber, means for conveying a solution comprising said second liquid, 30 said absorbent and said refrigerant to said evaporator, and means for supplying said first liquid to said evaporator, said absorbent and first liquid having a greater affinity for each other at the temperature obtaining in 35 said evaporator than the affinity between said absorbent and said second liquid whereby said absorbent passes from solution with said second liquid to solution with said first liquid and said refrigerant passes into the vapor 40 state.

13. Refrigerating apparatus comprising a heated vessel, an absorber, an evaporator, means for supplying a first solution comprising an absorbent and a first liquid to said 45 heated vessel, means for supplying a second liquid to said heated vessel, means for conveying a second solution comprising said absorber and said second liquid from said heated vessel to said absorber, means for supplying vaporous refrigerant to said absorber, 50 means for conveying a third solution comprising said absorbent, said second liquid and said refrigerant from said absorber to said evaporator and means for conveying said first liquid from said heated vessel to said evaporator.

14. Refrigerating apparatus comprising a heated vessel, an absorber, an evaporator, means for circulating an absorbent in solution from said heated vessel through said absorber to said evaporator, means for circulating refrigerant in solution from said absorber to said evaporator and means for circulating absorbent in solution from said 60 evaporator to said heated vessel.

15. The process of transforming energy which comprises the steps of circulating a fluid in a solution having a given pressure-temperature curve for conditions of operation, circulating some of the same fluid in a 70 second solution having a given pressure-temperature curve for conditions of operation which crosses the first-mentioned curve, transferring said fluid from one of the solution liquids to the other under conditions to 75 one side of the point of crossing of the curve and transferring said fluid in the other direction between the solution liquids under conditions on the other side of the point of crossing of the curves.

In testimony whereof I hereunto affix my signature.
